UNITED STATES PATENT OFFICE.

MICHAEL F. BROGAN, OF LAWRENCE, MASSACHUSETTS, ASSIGNOR TO UNITED SHOE MACHINERY COMPANY, OF PATERSON, NEW JERSEY, A CORPORATION OF NEW JERSEY.

WELT-BEATING MACHINE.

1,284,276.

Specification of Letters Patent. Patented July 24, 1917.

Application filed October 23, 1915. Serial No. 57,441.

To all whom it may concern:

Be it known that I, MICHAEL F. BROGAN, a citizen of the United States, residing at Lawrence, in the county of Essex and State 5 of Massachusetts, have invented certain new and useful Improvements in Welt-Beating Machines; and I do hereby declare the following to be a full, clear, and exact description of the invention, such as will enable 10 others skilled in the art to which it appertains to make and use the same.

This invention relates to welt beating machines, and more particularly to welt beating machines of the type in which the welt 15 beating means has an intermittent gripping engagement with the welt.

Welt beating machines of the type at present in common use in shoe factories comprise a welt support adapted to enter the 20 crease between the welt and upper of a lasted shoe, so as to support the welt upon its upper surface, and a welt beating hammer which is vibrated with great rapidity to beat out the welt as the welt is advanced 25 across the upper surface of the welt support.

In such machines the welt is advanced over the surface of the welt support between the strokes or blows of the hammer while the hammer is disengaged from the welt.

Young or inexperienced operatives are usually employed in shoe factories to operate these machines, and a great deal of trouble is caused by the operative's advancing the work so rapidly through the machine that 30 the operation is not efficiently performed. The operatives of such machines are apt to slight the work at certain points, particularly along the sides of the shoe, with the result that the welt is not in proper condition when the outsole is applied.

The objects of the present invention are to improve the construction and efficiency of welt beating machines, and to produce a welt beating machine of the type having welt 45 beating means having an intermittent gripping engagement with the welt in which it will be impossible for the operator to advance the welt more rapidly than a predetermined speed.

With this object in view, one feature of the invention contemplates the provision in a welt beating machine in which the welt beating means has an intermittent gripping engagement with the welt of means for lim-

iting the speed at which the welt may be fed 55 through the machine.

In the preferred form of the invention the feed limiting means consists of welt feeding devices which are engaged with the welt before the welt is released by the 60 welt beating means during each cycle of the machine, and act to advance the welt while the welt beating means is disengaged from the welt.

Certain parts of the welt which are especially refractory, such as that around the toe of the shoe, require a more extended beating than the rest of the welt, in order to reduce these parts to the proper condition during the beating operation. To enable 70 this result to be secured, the invention contemplates the provision of mechanism for controlling the welt feeding devices to vary the speed at which the welt is advanced during the operation of the machine. The 75 mechanism for controlling the welt feeding devices is preferably under the control of the operator, so that the speed may be increased or decreased at any desired point in the welt.

Further features of the invention consist of certain constructions, arrangements and combinations of parts hereinafter described and particularly pointed out in the claims, the advantages of which will be obvious to 85 one skilled in the art.

The invention will be readily understood from the accompanying drawings illustrating a machine embodying the invention in its preferred form, and the following detailed description.

In the drawings,

Figure 1 is a view in side elevation of a welt beating machine embodying the invention;

Fig. 2 is a view in front elevation, partly in section, of the machine; and

Fig. 3 is a detail plan view, partly in section, illustrating particularly the welt feeding devices.

The machine illustrated in the drawings is a welt beating and slashing machine, the beating and slashing mechanisms of which have the same general construction and mode of operation as the beating and slashing mechanisms of the machine illustrated in the patent to Hadaway, No. 875,171, December 31, 1907. The machine comprises a

work support indicated at 2, the forward end of which is shaped to enter the crease between the upper and welt of a lasted shoe to support the welt on its upper surface. 5 The welt beating hammer is indicated at 4, and is secured to the lower end of the hammer rod 6 which is mounted in the forward end or head of a hammer lever 8. A coiled spring 10 surrounds the hammer rod and engages at its lower end a collar 12 formed on the rod, and at its upper end an adjustable sleeve 14 which is threaded into the head of the hammer lever and held in adjusted position by a lock nut 16. The downward 10 movement of the hammer rod in the hammer lever is limited by the engagement of a stop collar 18 threaded on the upper end of the hammer rod with the sleeve 14.

The hammer lever 8 is mounted to oscillate on a shaft 20 journaled in bearings 22 in the machine frame. The rear end of the hammer lever is formed with spread arms to receive between them an eccentric block 24 embracing an eccentric on the main shaft 26 of the machine. This construction serves 25 to oscillate the hammer lever 8 rapidly during the rotation of the main shaft 26.

The machine is provided with a welt slashing knife 28 which is secured to the forward end of the reciprocatory slide 30, the rear end of which is connected with an oscillatory lever 32 pivoted at 34 and provided with a cam roll 36 engaging the cam groove 38 in a cam disk 40 mounted to turn loosely upon the rearwardly extending shaft 42 fixed in the frame of the machine. The main shaft 26 of the machine carries a worm meshing with a worm wheel 44 mounted on the rearwardly extending shaft 42 alongside 30 the cam disk 40, and a sliding clutch pin 46 mounted in the cam disk 40 and arranged to be moved into and out of clutching engagement with the worm wheel 44 is provided to connect the cam disk with the worm wheel 45 at certain times, so that the cam disk may be actuated to operate the welt slashing knife. The action of the clutch pin is controlled by a wedge 48 mounted upon the extremity of a lever 50 pivoted on the shaft 50 52 and normally held in elevated position by a tension spring 54 to maintain the clutch pin 46 disengaged from the worm wheel 44. The lever 50 may be depressed to allow the clutch pin to be actuated by a spring 54^a to engage the worm wheel 44 and thereby connect the cam disk with the worm wheel through suitable connections with a treadle (not shown).

The feed limiting mechanism of the machine illustrated in the drawings comprises a pair of welt gripping and feeding jaws indicated respectively at 58 and 60. These jaws are arranged to grip the welt at a point immediately in advance of the welt support, 65 and are mounted for movement in the direc-

tion of the line of feed to feed the welt. The lower jaw 58 is formed at the end of a curved arm 62 secured by means of a bolt 64 to a dove-tailed slide 66 mounted in a suitable guideway in the frame of the machine extend substantially parallel with the line of feed. The upper jaw 60 is formed at the end of a curved arm 68 pivoted to the arm 62 by means of a horizontal pivot pin or bolt 70. The upper or movable jaw 60 of the gripping device is moved relatively to the lower or fixed jaw 58 to grip the welt just before the hammer is raised from the welt during each cycle of operation of the machine. While the hammer is disengaged from the welt the slide 66 is moved to the left (Fig. 2) or in the direction of feed, the jaws of the gripping device being maintained in gripping relation with the welt during this movement of the slide. The advancing movement of the feed jaws while the welt is gripped between them acts to advance the welt across the upper surface of the welt support 2. When the hammer has again engaged the welt, the upper jaw of the gripping device is lifted to release the welt from the grip of the jaws, and the slide 66 is then moved back to starting position. It will be noted that with this mode of operation of the gripping and feeding jaws relative to the hammer the welt is gripped at all times either between the hammer and the welt support or between the jaws of the gripping device, and that the speed at which the welt is advanced across the upper surface of the welt support is entirely controlled by the movement of the welt gripping jaws.

The upper jaw 60 of the gripping device is actuated to open and close the jaws through an oscillatory lever 72 pivoted at 74 upon an upwardly extending arm 76 on the frame of the machine, and connected at its forward end with a rearwardly extending arm 78 preferably formed integral with the arm 68. The rear end of the arm 78 is formed with a cylindrical bearing block 80 which fits in a suitably formed bore or bearing in a block 82 which in turn is slidably fitted in a recess in the forward end of the lever 72. The block 82 is connected with the bearing block 80 by means of a pin 84 passing through the block 82 and engaging in a slot in the bearing block 80 as shown in Fig. 3. This construction forms an efficient connection between the lever 72 and the arm 78 for moving the arm from the lever which will permit the free movement of the arm with the slide 66. The rear end of the lever 72 is pivotally connected at 86 with a clevis 88 having a bolt 90 which extends through the cross piece of a yoke 92. A coiled spring 94 surrounding the bolt 90 is interposed between the yoke 88 and a nut 96 threaded on the end of the bolt. The yoke 88 is pivot-

ally connected at 98 with the forwardly extending arm of a cam lever 100 pivoted on a reduced portion of the shaft 20, and having a cam roll 102 mounted on the end of its rearwardly extending arm which engages in the cam groove 104 in a cam disk 106 mounted on the main shaft 26. Through this mechanism the upper jaw of the gripping device is actuated to open and close the jaws 10 to grip and release the welt. The spring 94 provides a yielding connection between the cam lever 100 and the movable jaw of the gripping device which permits a relative yield between this jaw and the lever after the jaw engages and grips the welt, and enables the jaws to grip and hold securely welts of varying thicknesses.

The mechanism for reciprocating the slide 66 in timed relation to the relative opening 20 and closing movement of the jaws of the gripping device, so that the slide is advanced in the direction of feed while the welt is gripped between the jaws and is retracted while the jaws are open and the welt released, comprises a bell crank lever 108 pivoted upon a vertical stud 110 secured in the frame of the machine, the forwardly extending arm of which lever is formed with a slot 112 to receive the shank of the bolt 64 by which the arm 62 is secured to the slide 66. The laterally extending arm of the bell crank 108 is connected by a universal joint 114 with the forward end of a link 116. The rear end of this link is connected by a universal joint 118 with a block 120 mounted in an arc-shaped groove 122 in the upwardly extending arm of the bell crank lever 124 pivoted on the shaft 126. Oscillatory movements of substantially unvarying amplitudes are imparted to the bell crank lever 124 and through the connections described between this bell crank and the bell crank 108 the latter bell crank is oscillated to impart reciprocatory movements to the slide 40 66. The block 120 is mounted in the groove 122 in the upwardly extending arm of the bell crank 124, so that the block may be moved toward and away from the axis of the lever to vary the extent of movement 45 imparted through the block to the bell crank 108 and thereby vary the feed movements of the slide 66. Oscillatory movements are imparted to the bell crank lever 124 through a link 128 connected at one end with the 50 rearwardly extending arm of the bell crank lever, and at the other to the shorter arm of a two-armed lever 130 pivoted on the shaft 20 outside of the lever 100. The other arm of this two-armed lever is provided with a cam roll 132 engaging a cam groove 134 in the cam disk 106.

To enable the operator to control the speed at which the welt is fed through the machine, so that the degree or extent of the 55 beating action to which the welt is sub-

jected may be varied at different points in the welt, a connection is provided between the block 120 and a treadle (not shown) by which the operator may control the position of the block in the groove 122. In the construction shown, the block is connected by a link 134 with the arm 136 of a lever pivoted upon the stud 138. This lever is provided with a second arm 140 to which a treadle is connected. Separate treadles may be provided respectively to control the throwing of the welt slashing mechanism into and out of operation and to control the speed at which the welt is fed by the welt feeding devices. The welt of a lasted shoe is ordinarily most refractory at the toe where the strain upon the outer edge of the welt gives the welt a curved cross section, and this part of the welt requires a more extended beating than any other part in order to reduce 70 it to the proper condition. It is, therefore, practically essential to the efficient beating out of the welt about the toe of the shoe that the speed at which the welt is advanced across the upper surface of the welt be reduced to a minimum when operating on this portion of the welt. The welt slashing mechanism of the machine is ordinarily thrown into operation only when operating about the toe, the slashes being formed in the 75 toe portion of the welt to enable the outer edge of the welt to stretch more readily under the action of the beating mechanism. In the present construction the welt slashing mechanism and the welt feeding mechanism are connected with a single treadle, and the connections are so arranged that the treadle may be actuated to vary the feed between certain limits while the welt slashing mechanism is inactive, but so that when the treadle is actuated to give a minimum length of feed the welt slashing mechanism is thrown into operation. In the construction shown the arm 140 is formed with a lug 80 142 to which is connected the upper end of the treadle rod 144. The lever 50 which controls the operation of the welt slashing mechanism is connected with the arm 140 by a link 146 pivoted at its upper end to the lever and having a slot 148 at its lower end which receives a pin 150 mounted in the end of the arm 140. With the lever 50 in elevated position, as shown in the drawing, so as to maintain the welt slashing mechanism in an inoperative condition, the 85 treadle may be operated to vary the length of feed within the limits prescribed by the ends of the slot 148. When, however, the pin 150 engages the lower end of the slot 148 and the treadle is depressed to shorten 90 still further the length of feed, the lever 50 will be swung downwardly, thereby throwing the welt slashing mechanism into operation.

The above construction and arrangement 95

of parts enables the extent of the beating action to which the welt is subjected to be varied as desired when operating along the sides of the shoe, and the toe portion of 5 the welt to be beaten out quickly and easily even by an inexperienced operator.

Having explained the nature and object of the invention, and having specifically described a machine embodying the same in 10 its preferred form, what is claimed is:—

1. A welt beating machine, having, in combination, a welt support, welt beating means having an intermittent gripping engagement with the welt, and means for limiting the speed at which the welt may be fed 15 through the machine.

2. A welt beating machine, having, in combination, a welt beating hammer, means for operating the hammer, and means for 20 limiting the distance which the welt may be fed between the blows of the hammer.

3. A welt beating machine, having, in combination, a welt support, welt beating means having an intermittent gripping engagement with the welt, and means for 25 limiting the speed at which the welt may be fed through the machine comprising laterally movable welt gripping jaws and means for determining the lateral movement of the 30 jaws.

4. A welt beating machine, having, in combination, a welt support, welt beating means having an intermittent gripping engagement with the welt, means for limiting 35 the speed at which the welt may be fed through the machine comprising laterally movable welt gripping jaws, means for operating the jaws to grip the welt, and means for moving the jaws laterally to feed the 40 welt.

5. A welt beating machine, having, in combination, a welt support, welt beating means having an intermittent gripping engagement with the welt, and means for 45 limiting the speed at which the welt may be fed through the machine, comprising laterally movable welt gripping jaws, means for operating the jaws to grip the welt during each cycle of operations while the 50 welt beating means is out of engagement with the welt, and to release the welt after the welt beating means has engaged the welt, and means for limiting the lateral movement of the jaws.

55 6. A welt beating machine, having, in combination, a welt support, welt beating means, and means for limiting the speed at which the welt may be fed through the machine, comprising laterally movable welt 60 gripping jaws, means for operating the jaws to grip the welt while the welt beating means is out of engagement with the welt, and to release the welt after the welt beating means has engaged the welt, and 65 means for moving the jaws laterally in

timed relation to the gripping and releasing movement of the jaws to feed the welt.

7. A welt beating machine, having, in combination, a welt support, welt beating means, devices for feeding the welt, and mechanism for controlling the speed at 70 which the welt is fed by the welt feeding devices.

8. A welt beating machine, having, in combination, a welt support, welt beating means, devices for feeding the welt, and mechanism under the control of the operator for varying the speed at which the welt is fed by the welt feeding devices during 75 the operation of the machine.

9. A welt beating machine, having, in combination, a welt support, welt beating means, means for slashing the welt, and means for limiting the speed at which the welt may be fed through the machine. 80

10. A welt beating machine, having, in combination, a welt support, welt beating means, means for cutting transverse slashes in the welt, and means for feeding the welt. 85

11. A welt beating machine, having, in combination, a welt support, welt beating means, welt slashing means, devices for feeding the welt, mechanism for producing variations in the speed at which the welt is fed by the welt feeding devices, mechanism for throwing the welt slashing means into and out of operation during the continued operation of the machine, and common means for controlling both said mechanisms. 90

12. A welt beating machine, having, in combination, a welt support, welt beating means, welt slashing means, devices for feeding the welt, mechanism for producing variations in the speed at which the welt is fed by the welt feeding devices, mechanism for throwing the welt slashing means into and out of operation during the continued operation of the machine, and common means under the control of the operator for controlling both said mechanisms. 100

13. A welt beating machine, having, in combination, a welt support, welt beating means, welt slashing means, devices for feeding the welt, mechanism for producing variations in the speed at which the welt is fed by the welt feeding devices, mechanism for throwing the welt slashing means into and out of operation during the continued operation of the machine, and a connection for causing the welt slashing means to be thrown into operation when the speed at which the welt is fed is reduced to a predetermined speed. 110

14. A welt beating machine, having, in combination, a welt support, welt beating means, welt slashing means, devices for feeding the welt, mechanism for producing variations in the speed at which the welt 120

is fed by the welt feeding devices, mechanism for throwing the welt slashing means into and out of operation during the continued operation of the machine, and a connection for causing the welt slashing means to be thrown into operation when the speed at which the welt is fed is reduced to a predetermined speed.

15. A welt beating machine, having, in combination, a welt support, welt beating means, devices for feeding the welt, and

mechanism for producing variations in the speed at which the welt is fed by the welt feeding devices during the operation of the machine.

15

16. A welt beating machine, having, in combination, a welt support, welt beating means having an intermittent gripping engagement with the welt and means for feeding the welt relatively to the welt beating means.
